US00D875277S

(12) **United States Design Patent** (10) Patent No.: **US D875,277 S**
 Sheehan et al. (45) Date of Patent: **** Feb. 11, 2020**

(54) **FORMLINER**

(71) Applicant: **PRIME FORMING & CONSTRUCTION SUPPLIES, INC.**,
 Santa Ana, CA (US)

(72) Inventors: **Brian Eugene Sheehan**, Mission Viejo, CA (US); **Edward Daniel Fitzgerald**, Laguna Beach, CA (US)

(73) Assignee: **PRIME FORMING & CONSTRUCTION SUPPLIES, INC.**,
 Santa Ana, CA (US)

(**) Term: **15 Years**

(21) Appl. No.: **29/609,516**

(22) Filed: **Jun. 30, 2017**

(57) CLAIM

The ornamental design for a formliner, as shown and described.

DESCRIPTION

FIG. 1 is a top-front perspective view of a first embodiment of the design for a formliner;

FIG. 2 is a front view thereof;

FIG. 3 is a rear view thereof;

FIG. 4 is a top view thereof;

FIG. 5 is a bottom view thereof;

FIG. 6 is a left-side view thereof; and

FIG. 7 is a right-side view thereof.

FIG. 8 is a top-front perspective view of a second embodiment of the design for a formliner;

FIG. 9 is a front view thereof;

FIG. 10 is a rear view thereof;

FIG. 11 is a top view thereof;

FIG. 12 is a bottom view thereof;

FIG. 13 is a left-side view thereof; and

FIG. 14 is a right-side view thereof.

FIG. 15 is a top-front perspective view of a third embodiment of the design for a formliner;

FIG. 16 is a front view thereof;

FIG. 17 is a rear view thereof;

FIG. 18 is a top view thereof;

FIG. 19 is a bottom view thereof;

FIG. 20 is a left-side view thereof; and,

FIG. 21 is a right-side view thereof.
